(57) **CLAIM**

The ornamental design for an electric fence insulator, as
shown and described.

DESCRIPTION

FIG. 1 is a front view of an ornamental electric fence insulator
showing my new design;

FIG. 2 is a rear view thereof;

FIG. 3 is a top view thereof;

FIG. 4 is a bottom view thereof;

FIG. 5 is a first side view thereof;

FIG. 6 is a second side view thereof;

FIG. 7 is a first perspective view thereof; and,

FIG. 8 is a second perspective view thereof.
